UNITED STATES PATENT OFFICE.

**CHARLES M. STEVENSON, OF ROCKFORD, ILLINOIS, ASSIGNOR TO IOWA GATE COMPANY,
OF CEDAR FALLS, IOWA, A CORPORATION OF IOWA.**

DESIGN FOR A STALL PARTITION.

53,947.

Specification for Design.

Patented Oct. 7, 1919.

Application filed May 28, 1917. Serial No. 171,592. Term of patent 14 years.

To all whom it may concern:

Be it known that I, CHARLES M. STEVENSON, a citizen of the United States, residing at Rockford, in the county of Winnebago and State of Illinois, have invented a new, original, and ornamental Design for Stall Partitions, of which the following is a specification, reference being had to the accompanying drawing, forming part thereof.

The figure is a perspective view of a stall partition showing my new design.

I claim:

The ornamental design for a stall partition as shown.

CHARLES M. STEVENSON.
